UNITED STATES PATENT OFFICE

GREGORY LANG, OF YUBA CITY, CALIFORNIA

BEAN CUTTER

Application filed February 11, 1930. Serial No. 427,499.

This invention relates to horse or tractor drawn bean cutters, and particularly represents improvements over my Patent No. 1,781,851, dated November 18, 1930.

The principal objects of this invention are to provide an improved and simplified construction and mounting of the front end ground engaging tips of the runners and vine engaging rollers, so that these parts will be better able to withstand the strains and wear incident to use and so that the tips may be vertically adjusted; to provide a simple means for detachably securing the cutting blades to the runners so that said blades may be easily removed for resharpening; to provide a stronger yet simplified main frame; to provide a more rigid and substantial means for adjusting the vertical setting of the supporting wheels; to provide a vertically and longitudinally adjustable seat for the operator of the cutter; and to provide a tongue mounted so that the height of the same at its front end may be altered to suit different conditions.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved bean cutter.

Fig. 2 is a top plan view of the same.

Fig. 3 is a longitudinal section of the main frame at the center showing the mounting and control of the tongue and the mounting of the adjustable seat.

Fig. 4 is an enlarged longitudinal section of a ground engaging tip shown in connection with the adjacent parts.

Fig. 5 is a cross section on the line 5—5 of Fig. 4 looking forward.

Fig. 6 is an enlarged cross section of a runner showing the detachable securing means for a cutting blade.

Fig. 7 is a fragmentary perspective view of a blade detached.

Referring now more particularly to the characters of reference on the drawings, the

numeral 1 denotes the central longitudinal member of the main frame—an upwardly facing channel beam or a pair of angle irons arranged in close relation to form a channel. Rigidly secured to this member are longitudinally spaced transverse beams 2 which are preferably of angular form, but other forms, such as square pipe, may be used instead.

Side beams 3 parallel to the member 1 are secured on the cross beam 2 equal distances to the sides of said member and from the front of the forward beam 2 they are bent so as to converge toward the forward end of the central member 1, as at 4, to the sides of which member they are rigidly secured. A cross strap 5 is secured to the under faces of the members 1 and 4 adjacent their forward ends and forms a connection for the forward ends of brace straps 6 which extend under and are rigidly connected to the adjacent beam 2 and diverge to their rear ends, at which ends they are rigidly connected with the beams 3 substantially midway between the beams 2. Just forwardly of the strap 5 a transverse yoke 7 is secured to the under face of the member 1, forming with said member a socket to receive and support a doubletree 8, from which the pull is transmitted to the front end of the frame.

Midway between the beams 2 the beams 3 support brackets 9, which in turn support a transversely extending sleeve 10. The braces 6 are secured to the beams 3 in common with said brackets so as to provide a unitary connection between these parts. Turnable in the ends of the sleeve are shafts 11 having downwardly and outwardly angled arms 12 at their outer ends, on the lower ends of which flanged wheels 13 are mounted. The flange of each wheel is provided with a row of holes 14 so that laterally extending cutting blades may be removably secured to the wheels if desired.

Supported from the under side of the beam 3 ahead of the sleeve 10 is a shaft 15 on which, outwardly of the beams, short sleeves 16 are turnable. Each sleeve has opposed radially extending arms at its opposite ends, the inner one of which projects upwardly and serves as a control lever 17, and the other one, 18, depends from the sleeve and is connected at

its lower end to the lower end of the corresponding wheel supporting arm 12 by a link 19.

The lever 17 is associated with a pawl and quadrant device 20 so that it may be held in any position.

A tongue 21 normally rests on the member 1 and fits closely between the sides thereof. This tongue intermediate its ends is pivotally connected to the member 1 by one of the bolts 22 which connects the members 4 to said member 1, so that the lift on the tongue is transmitted to the frame at the foremost end of the same. It will be noted that what appears to be a pair of bolts 22 is shown as connecting each member 4 to the central member 1. It will be understood however that only one of such bolts is continuous between the members 4, so as to serve as a pivot for the tongue. The other bolt, for each member 4, is merely a short stub, connecting the adjacent or abutting flanges of the member 4 and the central member 1, the latter as previously stated, being formed of two angle bars.

Turnable on the sleeve 10 in the longitudinal plane of the tongue is a pinion 23 engaging a segmental gear 24 fixed on the adjacent end of the tongue. A lever 25 is fixed with and projects upwardly from one end of the pinion, cooperating with a pawl and quadrant device 25a of the common character so that said pinion and consequently the tongue may be held in any desired position. It will therefore be seen that upon turning the lever the tongue will be tilted about the pivotal bolt 22, causing the front end of the tongue to be lowered relative to its normal lined position in the frame member 1. Since the front end of the tongue is maintained at a certain level by reason of its connection with the draft animals, this tilting of the tongue has the effect of raising the front end of the cutter frame. The seat structure associated with the frame comprises longitudinally extending side straps 26 straddling the member 1 rearwardly of the tongue and at their rear ends supporting the longitudinally adjustable seat 27. Toward their forward ends these straps are connected by cross straps 28, one above and one below the straps 26 in longitudinally spaced relation; one of said straps 28 being usually disposed toward the rear end of the member 1, as shown in Fig. 3. The straps 28 normally ride on the upper and under surfaces respectively of the member 1, the seat supporting straps 26 being then substantially horizontal as indicated in dotted lines in Fig. 1.

The straps 28 are freely slideable along the member 1 when the weight is off the seat, but will not slip when the seat is occupied on account of the frictional resistance offered by the engagement of said straps with said frame member. The seat therefore can be easily adjusted to accommodate users of dif-

ferent leg length, arm reach, or weight, while maintaining the seat on the same horizontal level. To enable the straps 26 to be disposed at an upward slope, so that the seat will be higher, I provide removable bolts 29 through 70 said straps below and above the rear and front straps 28 respectively, which then engage the upper and lower surfaces of the member 1 in place of the straps 28, as shown in Fig. 3. To enable the seat to be then horizontally disposed or in its normal seating position the rear end of the straps 26 are bent down as shown at 80, so that when the straps 26 assume the angular position and the seat is slid rearwardly along the same to rest on the said bent portion the seat will reassume the desired horizontal position. This mounting of the seat also enables it to be swung forwardly when not in use if it is desired to get it out of the way. 85

Depending from the beams 2 outwardly of the beams 3 are standards 31, secured to said beams for transverse adjustment in the same manner as in said Patent No. 1,781,851, and braced against longitudinal deflection by 90 tension rods 32 which may be of an adjustable or non-adjustable type as may be desired. Bolted to the lower ends of these standards are longitudinally extending wooden runners 33, set on edge and adapted 95 to rest on the ground only when the machine is not in operation. Horizontal blades 34 sharpened along their forward edges converge toward their rear ends from the inner faces of the runners intermediate the ends 100 thereof. At their forward ends the blades are formed with upstanding but forwardly sloping plates 35 abutting against the inner faces of the runners; said plates being also sharpened along their under forward edges. 105

Each plate is provided with a pair of vertically spaced horizontally extending key-hole openings 36, the enlarged portions of which receive the heads of bolts 37 therethrough, while the smaller portions are of 110 sufficient size to only receive the shanks of the bolts. The bolt shanks are square except for the threaded portion on their outer ends, so as to be slideable but non-turnable in the runner. The lower bolt projects through the 115 blade plate runner and through the sides of metal angle members 38 with which the adjacent portion of the runner is sheathed at the bottom. The upper bolt projects through the blade plate, the runner and the 120 adjacent standard 31, as shown in Fig. 1. Each bolt has a flanged nut 39 on its outer end, the flange of which is held against removal or outward movement, without preventing the nut being turned by a wrench, 125 by a keeper 40 secured to the member 38 or the upright 31 as the case may be. To remove a blade therefore it is only necessary to retract the nuts relative to the threads of the bolts. This will cause the bolts to be shifted 130

inwardly, so as to unclamp the bolt heads from the plate 35. The plate may then be shifted horizontally until the enlarged portions of the openings 36 aline with the heads of the bolt, when an inward movement of the 5 blade plate will clear the same from the heads of the bolts.

Mounted in rigid connection with each runner at the front end of the same is a cast 10 tip 41, of substantially U-shaped form in a horizontal plane. This tip straddles the forward end of the runner, leaving a space 42 between said end and the solid metal across the forward end of the tip, as shown in Fig. 15 4. At said forward end the tip has a downward and forward slope, and depends a short distance below the level of the runner and the sheathing plates 38. These plates extend ahead of the runner and terminate 20 close against the angled inner face of the front end portion of the tip. The rearward pressure exerted on the tip as it engages the ground is therefore taken direct by the rigid plates 38 instead of by the bolts 43 which are 25 used to adjustably clamp the tip to the runner and plates.

Also the bottom flanges of the plates 38 serve to close the space 42 at the bottom so that no dirt can enter said space from below. 30 The bolts 43 are disposed in longitudinally and vertically offset relation, the lower one passing through the sides of the plates 38 and the tip, and the upper one passing through the tip and runner. The bolt holes 35 44 in the tip are formed as oblong slots, whose major axes are parallel to the slope of the front end of the tip. This enables the vertical setting of the tip relative to the runner to be altered, while still maintaining the front edges of the plates 38 in close 40 engagement with the inner surface of the front end of the tip for the purpose previously set forth.

Mounted on the lower bolt 43, which is in 45 the space 42, is a T member 45, in which is secured a tension rod 46 projecting upwardly to a rigid connection with a bracket 47 secured to the upper end of the adjacent stand- 50 ard 31. Turnable on the rod in the same manner as said copending application is a roller 48 resting on the T. The sides of the tip in the plane of the space 42 are orificed as at 49 so as to provide for the ready exit of any dirt which may possibly become lodged in 55 said space and thus prevent the dirt from possibly jamming about the bearing of the roller and interfering with its free rotation. At the same time said bearing is below the upper end of the tip so that it is protected from direct 60 contact with the dirt or vines engaged by the tip during its forward movement.

By reason of the tongue adjusting features previously described the angular setting of the machine as a whole relative to the ground 65 may be altered so as to correspondingly alter

the angular setting of the runners and cutting blades relative to the ground, as may be necessary or desirable when operating under varying conditions.

The particular arrangement of the braces 6 I believe to be an important feature. They hold the frame rigid against twisting deflection in a vertical plane, and prevent the beams 3 from bending up at the brackets 9, or from bending down at the points where the beams 2 are connected thereto and thus prevent the tips 41 (which are supported from the beams 3) from digging too deep into the ground. This construction also has other bracing features, and enables the frame as a 70 whole to be kept relatively light without loss of strength or rigidity. It is to be noted that in this cutter, no weight is supported by the runners, the cutter being held up by the 75 wheels and the tongue when in motion. The runners are for the purpose of forming a rigid means to which to attach the tips or points, the dividing rollers, and the blades.

Though I have described and particularly 80 intend this machine as being for cutting beans, it is also suitable with little or no modification, except as to the proportioning or sizes of the parts, for cutting spinach and similar crops.

While this specification sets forth in detail 85 the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In an agricultural implement, a main longitudinal frame member, a seat, transversely spaced longitudinally extending supports on the rear end of which the seat is mounted, and means between said supports and the member for adjustably mounting said supports on said member at different points in the length of the latter and so that the seat may be independently disposed at different levels.

2. In an agricultural implement, a main longitudinal frame member, a seat, transversely spaced longitudinally extending supports on the rear end of which the seat is mounted, said supports extending forwardly from the seat in straddling relation to said member, and longitudinally spaced straps secured to and extending between the supports from the upper and lower edges of the same to engage the upper and lower surfaces respectively of the frame member.

3. A structure as in claim 2, with additional longitudinally spaced removable members placeable through the supports intermediate their top and bottom edges to engage the frame member independent of the straps.

4. In a bean cutter having transverse

shafts, downwardly depending arms on the outer ends of the shafts, and wheels supported from the lower ends of the arms; a shaft parallel to but longitudinally spaced from the wheel-shafts, a sleeve for each wheel turnable on the last named shaft, a lever projecting upwardly from one end of the sleeve, an arm depending from the other end of the sleeve, and a link between the lower end of

10 said arm and the wheel-shaft arm.

5. In a bean cutter having side runners set on edge and adjacent the ground, and cutting blades projecting downwardly and inwardly from the runners; upstanding plates on the forward ends of the blades abutting against the inner faces of the runners, said plates having key-hole openings therein, bolts through the runners and openings and whose heads are passable through the enlarged ends of the openings, nuts on the outer ends of the bolts and keepers for the nuts to prevent outward movement of the same without interfering with their rotation; the bolts being slideable but non-turnable in the runners.

6. In a bean cutter having side runners set on edge and adjacent the ground, and cutting blades projecting downwardly and inwardly from the runners; upstanding plates on the forward ends of the blades abutting against the inner faces of the runners, said plates having keyhole openings therein, bolts through the runners and openings and whose heads are passable through the enlarged ends of the openings, said bolts being slideable but non-turnable in the runners, and means operable from the outer faces of the runners for thus sliding the bolts to move their heads from a plate clamping to a plate releasing position and vice-versa.

7. In a bean cutter having side runners set on edge and adjacent the ground, individual tip members separate from said runners straddling the same at their forward ends, and means securing the tips to the runners for vertical adjustment.

8. In a bean cutter having side runners set on edge and adjacent the ground, tip members separate from said runners straddling the same at their forward ends, said members being substantially U shaped in a horizontal plane and each being disposed relative to its runner to leave an open space between the forward edges of the runner and the front cross web of the member, sheathing element across the bottom of the runner at the front and partially up the sides of the same, said elements extending ahead of the runner to cover the bottom of said space and about

50 against said cross-web, and bolts securing the tip to the runner and sheathing elements.

9. A structure as in claim 8, in which the bolt holes in the tip are of slotted form and extend parallel to the vertical plane of the crossweb.

10. In a bean cutter having side runners set on edge and adjacent the ground, tip members separate from said runners straddling the same at their forward ends, said members being substantially U shaped in a horizontal plane and each being disposed relative to its runner to leave an open space between the forward edges of the runner and the front cross web of the member, a substantially vertical roller projecting upwardly from and depending into said space, and bearing means in the tip for the lower end of the roller; there being openings in the sides of the tip in the plane of the space and bearing means.

11. In a bean cutter having side runners set on edge and adjacent the ground, tip members separate from said runners straddling the same at their forward ends, said members being substantially U shaped in a horizontal plane and each being disposed relative to its runner to leave an open space between the forward edges of the runner and the front cross web of the member, a bolt fixed with each tip and projecting across the space, a T member mounted on the bolt in said space, a vertical tension rod secured at its lower end in said T, and a roller turnable on the rod and resting on the T; the top of the T being below the top of the tip.

12. In a bean cutter having side runners set on edge and adjacent the ground, one-piece tip members separate from said runners extending ahead of the same and secured to the forward ends thereof, said members depending to the plane of the bottom of the runners to engage the ground ahead of the latter.

13. In a bean cutter having side runners set on edge and adjacent the ground, one-piece tip members separate from said runners extending ahead of the same and secured to the forward ends thereof, and rollers projecting upwardly from and supported at their lower ends by the tip members.

14. In a bean cutter, a main frame structure including a central longitudinal beam, side beams spaced from the central beam and converging toward their forward ends to connections with said central beam at its forward end, a cross beam connecting said central and side beams intermediate their ends, a cross strap connected to and under said beams adjacent their forward ends, braces secured to said straps and diverging thence to the side beams rearwardly of the cross beam, and connected to said side and cross beams, and means for applying a draft to the central beam ahead of said strap.

15. In an agricultural implement, a main longitudinal frame member, a tongue extending ahead of said member, a transverse pivot connection between said tongue intermediate its ends and the frame, a segmental gear on the rear end of the tongue concentric with

the pivot, a pinion meshing with the gear and journaled on the frame, a hand lever applied to the pinion for turning the same, and releasable catch means between the frame and lever to hold the latter at any desired position.

In testimony whereof I affix my signature.
GREGORY LANG.
